UNITED STATES PATENT OFFICE.

WILLIAM H. COLLINS, OF INDIANAPOLIS, INDIANA.

HORSE-HITCH.

No. 879,743.

Specification of Letters Patent.

Patented Feb. 18, 1908.

Application filed May 13, 1907. Serial No. 373,478.

To all whom it may concern:

Be it known that I, WILLIAM H. COLLINS, citizen of the United States, residing at Indianapolis, in the county of Marion and State 5 of Indiana, have invented certain new and useful Improvements in Horse-Hitches, of which the following is a specification.

The present invention relates to certain new and useful improvements in horse 10 hitches, and aims to provide a novel means for preventing the horse from dragging the weight.

With this object in view the invention resides principally in the provision of a pair of 15 levers which are pivotally mounted at an intermediate point upon the rings of a snaffle bit, the inner ends of the two levers being loosely connected while the outer ends are designed to be connected by links to the end of 20 a hitching strap in such a manner that any tension in the latter operates to force the inner ends of the levers upwardly against the lower jaw of the horse.

For a full description of the invention and 25 the merits thereof and also to acquire a knowledge of the details of construction and the means for effecting the result, reference is to be had to the following description and accompanying drawings, in which:

30 Figure 1 is a perspective view of the improved horse hitch. Fig. 2 is a front elevation of the same on a slightly reduced scale.

Corresponding and like parts are referred to in the following description and indicated 35 in all the views of the drawings by the same reference characters.

The invention is illustrated as applied to a snaffle bit comprising the rein rings 1 connected by the jointed bit bars 2. A lever 3 40 is passed through each of the rein rings 1 and is crimped at an intermediate point as indicated at 4 to receive the said ring and prevent longitudinal displacement of the lever. The inner ends of the levers 3 extend under

the lower jaw of the horse and are formed 45 with looped eyes 5 whereby a loose joint is produced. The outer ends of the levers 3 are provided with eyes 6 having link members 7 applied thereto, the said link members converging downwardly and engaging a ring 8 50 connected to the hitching strap 9. With this construction it will be readily apparent that any tension in the hitching strap 9 such as that produced when dragging the weight 10 will operate to pull the outer ends of the 55 levers 3 downwardly and force the inner ends upwardly against the lower jaw of the animal in such a manner as to cause it to cease pulling upon the hitching strap.

Having thus described the invention, what 60 is claimed as new is:

1. The combination of a bit comprising rings, levers fulcrumed at an intermediate point upon the rings and having their inner ends loosely connected, a hitching strap, and 65 link members connecting the hitching strap and the outer ends of the levers.

2. The combination of a bit comprising rings, levers provided at their intermediate portions with crimps receiving the rings, the 70 inner ends of the levers being loosely connected, a hitching strap, and connecting means between the hitching strap and the outer ends of the levers.

3. The combination of a bit comprising 75 rings, levers pivotally mounted at an intermediate point upon the rings and provided with crimped portions receiving the said rings, the inner ends of the levers being loosely connected, a hitching strap, and link 80 members connecting the outer ends of the levers and the hitching strap.

In testimony whereof I affix my signature in presence of two witnesses.

WILLIAM H. COLLINS. [L. s.]
